CLAIM

We claim the ornamental design for a lighting device, as shown and described.

DESCRIPTION

FIG. 1 is a front perspective view of a lighting device, showing our new design;

FIG. 2 is a front view thereof;

FIG. 3 is a left side view thereof;

FIG. 4 is a rear view thereof;

FIG. 5 is a right side view thereof;

FIG. 6 is a top view thereof; and,

FIG. 7 is a bottom view thereof.

The broken line showing is superimposed on the continuous surface of the claimed design, is for illustrative purposes only, and forms no part of the claimed design.
